(57) **CLAIM**

I claim the ornamental design for a filter, as shown and described.

DESCRIPTION

FIG. 1 is a front, top perspective view of a filter showing my new design;

FIG. 2 is a side view of the filter; and,

FIG. 3 is a top view of the filter.

The broken lines in the figures illustrate portions of the filter that form no part of the claimed design. The break lines in the figures represent indeterminate length and do not form part of the design.
